UNITED STATES PATENT OFFICE.

JAMES H. GEORGELIS, OF ALLSTON, MASSACHUSETTS.

SOLE AND HEEL TRIMMING MACHINE.

Application filed February 1, 1926. Serial No. 35,353.

This invention relates to improvements in shoe trimming mechanisms.

The primary object of this invention is the provision of an improved shoe trimmer, embodying novel guard and guiding means whereby the shoe may be accurately guided during the trimming or cutting operation, to prevent injury thereto.

A further object of this invention is the provision of an improved heel trimming unit for shoe trimming machines, embodying a novel flange or counter guard which may be so used in connection with the rotary cutter of the cutting machine as to prevent the cutter from cutting or scratching the covering of the heel during the trimming of the lift.

A further object of this invention is the provision of an improved shoe trimming machine unit, embodying a rotary cutter, and novel means to guard the shoe during the trimming or cutting operation, to prevent injury to the shoe.

A further object of this invention is the provision of an improved shoe trimmer or cutter, embodying novel guard means to facilitate the sole trimming of shoes, in an accurate and efficient relation.

A further object of this invention is the provision of an improved shoe cutting or trimming machine, including a rotary trimming cutter, with guard means rotatable therewith to facilitate both edge and sole trimming, and prevent injury to the shoe.

Other objects and advantages of this invention will be apparent during the course of the following detailed description.

In the accompanying drawing, forming a part of this specification, and wherein similar reference characters designate corresponding parts throughout the several views,

Figure 1 is a longitudinal sectional view taken thru the improved trimming cutter, showing the relation of parts during the trimming of a lift of a shoe.

Figure 2 is a fragmentary plan view of the details of the improved trimmer.

Figures 3 and 4 are transverse sectional views taken substantially on their respective lines in Figure 1 of the drawing.

Figure 5 is a fragmentary view showing more particularly means to lock the conventional slotted member of a rotary trimming cutter immovable with respect to the cutter.

Figure 6 is a detailed sectional view of a

rotary cutter, showing adjustable guide means to gage the bevel cutting of the sole of a shoe.

Figure 7 is a cross sectional view of details illustrated in Figure 6, in collapsed position.

Figure 8 is a simplified view of a guard sleeve placed upon a slotted member of a rotary cutter in simplified manner.

In the drawing, wherein for the purpose of illustration is shown only a preferred embodiment of the invention, the letter A may generally designate the improved trimming cutter, which may comprise a cutter head B connected for rotation with a rotary shaft C and including a novel retaining and guard means D in a cooperating relation therewith. An adjustable slotted frame E for receiving the cutter head B is mounted by means F on the shaft C in cooperative relation with the cutter B. Novel guard means G is provided upon the trimming cutter A to facilitate sole trimming and expedite the cutting operation.

The shaft C is of conventional form, at the free end thereof including a reduced tapered cutter receiving shank 10 and a tapered shoulder 11 between the shank 10 and the body 12 of the shaft C which tapers into the body 12 in a diverging relation therewith from the shank 10. The shank 10 at the free end thereof is provided with an inwardly extending screw threaded socket adapted to detachably receive the screw threaded shank 14 of a retaining screw 15.

The cutter B is of the conventional form, and it may include the tangentially disposed cutting blades 17, in spaced relation, the top peripheries of which may slope rearwardly in converging relation, and they may be shaped to conform to any cutting operation desired, and at the rear end of each blade an upwardly extending cutting projection 18 may be formed, normally adapted to be received in the spaces of the slotted member E, conventionally provided upon the rotary cutter A. The cutter head B also includes the sleeve portion 20 rigid with the blades 17, which receives therein the reduced shank 10 of the head B, and at its rear annular edge abuts against a retaining washer 21 which is held in position against movement longitudinally of the shaft C by abutment against the tapered shoulder 11.

As a means of retaining the cutter head B on the shaft C, the guard member D is provided, which serves the retaining func-

tion ordinarily provided on the conventional cutter, but which is formed differently in order to provide a guard to prevent mutilation of a shoe during the heel trimming or 5 other cutting operation. The member D is preferably of disc-shaped formation, including a central hub centering projection 18 adapted to fit in the sleeve 20; the member D having a central opening 25 therein for 10 receiving the screw threaded shank 14; the screw 15 including an enlarged head adapted to clamp the guard member D against the cutter B to retain the latter in position on the shaft C, as is obvious. It is at the outer 15 periphery or margin of the member D where the novelty of this invention appears. In conventional rotary trimming cutters, the retaining member which corresponds to the member D has a sharp outer edge, which 20 permits the cutter blades to mutilate the shoe during a trimming operation, and performs practically no guard function whatsoever. During the trimming of the lift 30 on the heel 31 of a shoe, as illustrated in 25 Figure 1, with the conventional rotary cutter, it is not easy to trim the heel properly, because of the sharp edge of the retaining disc or collar of the conventional cutter which enters the joint between the lift of 30 the shoe and the heel body and permits cutting of the lift farther inwardly than should be the case, and permits the cutting and scratching of the covering of the heel; very often ruining the heel of the shoe. To ob- 35 viate this the improved guard member D has a blunt peripheral edge 35, to prevent the member D entering the joint between the lift 30 and the body 31 of the heel, and therefore insures that the blades of the cutter B will efficiently cut the lift 30 to the proper gage, since the blunt periphery 35 of the member D will always engage the body 31 to prevent a too far cutting of the lift 30. The blunt edge 35 may be of various shapes, but at the corner 36 adjacent the corner edges of the blades 17, it is preferred that the member D project for about $\frac{1}{4}$ of an inch from the outer periphery of the blades 17. In the preferred instance 45 the peripheral edge 35 in width should conform to the contour of the body 31 of the heel, to contact the heel across the major width of the periphery 35, and prevent mutilation of the heel during the trimming 50 operation.

The slotted member E and the means F for retaining the same in position with respect to the cutter head B are conventional features, with the exception of means herein 60 employed, to retain the member E immovable longitudinally of the shaft C. The slotted member E conventionally consists of the spaced extensions 40, mounted on a cylindrical shaped body 41 which is externally 65 screw threaded at 42 inwardly from the end

of the member E opposite the extensions 40, for detachable connection with an internally screw threaded end of a sleeve 43 comprising part of the means F.

The means F includes a collar or abutment 45 adapted to be rigidly keyed upon the shaft C as by means of a set screw 46, which extends radially in projecting relation outwardly therethrough. The retaining sleeve 43 is provided with an annular 70 inwardly extending flange 47 at the end thereof remote from the cutter B which is adapted to abut against the end annular edge at the rear of the collar 45. When the slotted member E and the retaining sleeve 80 43 are in screw threaded engagement, they are adapted to contain a compression spring 48 under compression between the rear end edge of the body 41 of the slotted member E and the forward annular edge of the collar 45; the tendency of the spring 48 being to urge the slotted member E forwardly toward the cutter B; the member E being thus held in position by means of abutment 85 of the retaining flange 47 against the collar 45. This positions the rear ends of the blades 17, and particularly the extensions 18 of the cutter B in the spaces between the extensions 40 of the slotted member E, in accordance with conventional construction 90 well known to those skilled in the art to which this invention relates. In order to permit the longitudinal movement of the slotted member E upon the shaft to cover and uncover portions of the blades of the cutter B, a longitudinal slot 50 is formed in the retaining sleeve 43, as is illustrated in Figure 5 of the drawings, and the projecting end of the screw 46 is adapted 100 to ride along this slot 50 when it is desired that the slotted member E have a relative movement longitudinally of the shaft C toward and away from the cutter B to accomplish certain types of shoe trimming and cutting. However, in accordance 105 with the novelty of this invention it may be desired to hold the slotted member E against longitudinal movement with respect to the shaft C, and to this end a lateral slot 51 extends from the slot 50 at the rear end thereof, in an L-shaped relation with the length of the slot 50, and into which the upwardly extending end of the set screw 46 110 may be received, as illustrated in Figure 5 115 of the drawings, and it can then be readily understood that the retaining sleeve 43 is keyed to the shaft C against longitudinal movement, and consequently the member E cannot move longitudinally of the shaft C, but always holds a definite fixed relation 120 with respect to the cutter B, until the sleeve 43 is rotated to permit riding of the slot 50 relative to the set screw 46 when contained therein.

Referring to the guard means G, the same 130

includes a retaining sleeve or member 55 adapted to be adjustably secured upon the sleeve 43 of the means F in a set position thereon, to provide an annular abutment at the cutter facing edge 56 thereof, against which one end of a spiral compression spring 57 may abut in order to urge a guard sleeve 58 of the means G forwardly with respect to the cutter B, in order to provide a sole trimming guard therefor.

The retaining member or sleeve 55 may be held in adjusted fixed relation upon the retaining sleeve 43 by means of a set screw 60, as is illustrated in Figures 2 and 4 of the drawings. This sleeve or retaining member 55 has a slot 61 extending longitudinally thereof, into which the upper end of the set screw 46 may project, in order to permit access to the set screw 46; to permit assemblage of the retaining sleeve 55; and to permit of its adjustment longitudinally of the sleeve 43 to a desired set relation with respect thereto, in order to vary the tension of the spring 57.

The guard member 58 is of sleeve like formation, or hollow cylindrical in formation, and includes the enlarged forward portion 65, within which the slotted member E is received; the forward end of the portion 65 being entirely open, so that the portion 65 may ride over the rear end of the cutter B, in a shoe cutting guard relation with respect thereto. The forward edge 67 of the portion 65 is preferably flat, or blunt and arranged in a plane at right angles to the axis of the shaft C, and consequently the axis of rotation of the cutter B. This edge 67 provides a rest surface against which the surface of the shoe edge or heel may abut to guard and guide the position of the shoe during its cutting operation, as is readily apparent.

In order to insure that the surface 67 will be sufficiently wide it may be desired to provide an annular outwardly extending flange 69 at the front of the enlarged portion 65 of the guide member 58, as illustrated in the drawing; the front surface 67 arcuating into sloping relation along the flange 69. The member 58 also includes the rear portion 70 of sleeve-like formation, of less diameter than the portion 65, and at the juncture of the portions 65 and 70 a shoulder 71 is provided, tapering in converging relation from the portion 65 towards the portion 70, to provide an internal shoulder which is adapted to abut against the tapered shoulder 72 provided on the slotted member E, and facing away from the cutter B, as illustrated in Figure 1 of the drawing. The sleeve like portion 70 of the member 58 receives the portion 55 in telescopic relation therein, and the member 58 provides a shoulder 77 against which the other end of the spiral spring 57 abuts, in order to urge the member 58 for-

wardly against the shoulder 72, into guarding relation over the blades of the knife or cutter B.

It is readily apparent that during the sole trimming operation the top or guard member 58 plays an important part in guiding the shoe to gage the proper cutting of the sole. The member 58 of course moves longitudinally of the shaft C when pressure is brought to bear against the surface 67 by the edge of the shoe heel or sole; it being necessary to press against the guard member 58 in order to move the same rearwardly to expose the cutting blades for a sole cutting operation, and thus insuring that the shoe will not be damaged by reason of inaccurate cutting. The length of adjustment of the sleeve 58 may be regulated by adjustment of the member 55. To prevent rotation of the member 58 it is preferred to provide a radial pin 80 rigid on the member 55 which extends into a slot 81 extending inwardly from the rear edge of the guard cap or member 58, as illustrated in Figure 2 of the drawings.

It is within the contemplation of this invention to prevent the longitudinal movement of the member 58 with respect to the cutter B, and to this end a shallow opening or slot 83 is provided inwardly from the rear end of the member 58, as illustrated in Figure 2 of the drawings, to receive the pin 80, it of course being necessary to adjust the position of the member 55 in order to have this arrangement of parts. However, in this manner the member 58 may be placed so that its front guard or guiding edge 67 is placed in a vertical plane at any desired right angled relation with respect to the axis of the rotary cutter and the blades thereof, to most efficiently perform the cutting operation desired.

From the foregoing description of this invention it is apparent that a novel heel and sole trimming guard and guiding device has been embodied in a rotary trimming cutter, which embodies conventional features, and by means of which the sole and heel edge trimming may be more efficiently accomplished than with present cutter.

In Figures 6 and 7 is shown a rotary cutter head H supported upon a rotary shaft K in any approved manner. The slotted head or frame D' is mounted by the means F above described upon the shaft K, in a cooperative relation with the cutter H, and the guard means G' is provided upon the improved cutter, to facilitate trimming operations.

In so far as applicable the same reference characters have been given to the parts of Figures 6 and 7, as above described for the improved rotary cutter A, and the normal operation of the parts of the cutter illustrated in Figures 6 and 7 is the same as operation for the invention A.

Additional novelty is given to the cutter of Figures 6 and 7, in that the cutter blade portions of the slotted head or frame D' are provided with inclined cutting faces 80, 5 inclined with respect to the axis of the shaft K and cutter head H, and preferably sloping rearwardly from the front end of the cutter head F at an angle of 60° with respect to the horizontal axis of the shaft K. As is 10 illustrated in Figure 6, it is the purpose of the cutter head H and the slotted member D' to cut the soles 85 of a shoe M, with a bevel outer lower edge, as at 87, by moving the sole 85 against the sloping edges 80 of 15 the slotted member D' at the same time that the blades of the cutter H are cutting into the outer periphery of the sole 85. At the same time it is preferred that the side sleeve or member D' be set so that the outer blunt periphery 67 thereof bears a definite relation with respect to the cutting edge 80 of the slotted member D'. That is, it is preferred that 20 an inclined cutting portion of the edge 80 project outwardly of the plane of the guiding edge 67 when the sleeve G' is positioned in a definite guiding relation with respect to the slotted member D'; this tapered cutting portion which lies in such relation, of course, lying outwardly of the periphery of the 25 30 blades of the cutter head H in order to cut the bevel 87 on the sole 85, as can readily be understood. This bevel portion is indicated by numeral 90 in Figure 6 of the drawings. To hold the guide member G' or the sleeve G' in 35 this position, it is preferred to place an adjustable retaining screw or member 91 in a screw threaded opening 92 provided thru the tapered shoulder 71 of the guide sleeve G' which abuts against the internal inclined 40 shoulder 72 of the slotted member D', as illustrated in Figure 6 of the drawings. It is thus readily apparent that depending upon the length to which the adjusting screw 92 extends inwardly of the inner surface of the 45 shoulder 71, the guide sleeve G' may be adjusted with respect to the slotted member D', to variably position the blunt guiding edge 67 thereof with respect to the cutting surfaces of the cutter head H, and slotted 50 member D'.

As is illustrated in Figure 7 of the drawings, when the screw 91 is adjusted as to be out of engagement with the shoulder 72, to permit the shoulder 71 to move thereagainst, 55 the guiding member D' will be moved by its spring 57 forwardly to be entirely received within the compartment of the guide sleeve portion 65, and to render the cutting of the bevel on the sole 85 impossible. By 60 extending the screw 91 into the sleeve G' the degree of bevel cutting may be varied on the sole of the shoe.

Referring to Figure 8 of the drawings, the same shows the application of a special 65 type of guide sleeve N, where a particular

cutting operation upon a wooden heel is desired, and the rotary cutter is practically restricted to this use. The guide sleeve N in this case is used with a slotted member or frame E', which is associated in the same relation with the cutter head B, upon a rotary shaft C, as the slotted member E above mentioned for the form of invention A. The slotted member E', has the blades thereof provided with straight cutter faces 95, in a plane at right angles to the axis of the shaft C and cutter head B, although they may vary from this if desired. The guide member N, however, is fitted tightly, as by snug driving, or by other means, on the outer periphery 96 of the slotted head or frame E', so as to position the forward guiding surface 97 of the guide sleeve N flush with the forward edges 95 of the slotted member E'. In this manner the guide sleeve N is rigidly located with the slotted member E', in a permanent guiding relation, and all of the spring urged details of the above described forms of invention may be dispensed with. Otherwise the mounting of the cutter details illustrated in Figure 8 are the same as above described and similar reference characters have been applied thereto, in so far as consistent.

Various changes in the shape, size, and arrangement of parts may be made to the forms of invention herein shown and described, without departing from the spirit of the same or the scope of the claims.

I claim:

1. In a shoe trimming machine the combination of a shaft, a rotary trimming cutter on the shaft, a sleeve-like guard movable along the shaft including a sleeve-like portion forwardly open to receive the rotary cutter therein and providing a forward guide surface lying peripherally outwardly of the rotary cutter against which a shoe may rest during an edge cutting operation, spring means to urge the guide sleeve towards the rotary cutter to a predetermined guide position, and means for fixing the guide sleeve in a particular guiding and guarding relation with respect to the rotary cutter to prevent longitudinal movement of the sleeve with respect to the cutter.

2. In a trimming device of the class described a shaft, a rotary trimming cutter mounted on the shaft, a collar, means permitting adjustment of the collar on the shaft to a desired position thereon, a guard sleeve of substantially cylindrical formation, spring means between the said sleeve and the collar to urge the sleeve towards the rotary cutter, means to limit the movement of the sleeve towards the rotary cutter, said sleeve having a guide edge located peripherally outwardly of the cutter and against which a shoe may abut during its cutting operation, and means to hold the sleeve sta-

tionary against any movement longitudinally of the shaft.

3. In a trimming machine of the class described a shaft, a rotary cutting trimmer on the shaft, an abutment on the shaft, a slotted member movably associated in blade intermeshing relation with the rotary cutter, a sleeve connected with the slotted member adapted to engage against the said abutment to limit the movement of the slotted member forwardly towards the rotary cutter, spring means normally urging the said sleeve against said abutment and the slotted member forwardly towards the rotary cutter, said spring means permitting movement of the slotted member away from the cutter and longitudinally of said shaft, and guide means receiving the slotted member therein including an annular portion overlying the rotary cutter in peripherally spaced relation therewith and providing a shoe abutting surface adapted to act as a guard to prevent excess cutting of a shoe during a trimming operation.

4. In a trimming machine of the class described a shaft, a rotary cutting trimmer on the shaft, an abutment on the shaft, a slotted member movably associated in blade intermeshing relation with the rotary cutter, a sleeve connected with the slotted member adapted to engage against the said abutment to limit the movement of the slotted member forwardly towards the rotary cutter, spring means normally urging the said sleeve against said abutment and the slotted member forwardly towards the rotary cutter, said spring means permitting movement of the slotted member away from the cutter and longitudinally of said shaft, and guide means receiving the slotted member therein including an annular portion overlying the rotary cutter in peripherally spaced relation therewith and providing a shoe abutting surface adapted to act as a guard to prevent excess cutting of a shoe during a trimming operation, and spring means normally urging said guide means into such relation towards the cutter and permitting movement of the annular portion longitudinally of the shaft away from the cutter.

5. In a trimming machine of the class described a shaft, a rotary cutting trimmer on the shaft, an abutment on the shaft, a slotted member movably associated in blade intermeshing relation with the rotary cutter, a sleeve connected with the slotted member adapted to engage against the said abutment to limit the movement of the slotted member forwardly towards the rotary cutter, spring means normally urging the said sleeve against said abutment and the slotted member forwardly towards the rotary cutter, said spring means permitting movement of the slotted member away from the cutter

and longitudinally of said shaft, guide means receiving the slotted member therein including a sleeve overlying the rotary cutter in peripherally spaced relation therewith and providing a shoe abutting surface adapted to act as a guard to prevent excess cutting of a shoe during a trimming operation, and means to lock the slotted member to the shaft against any longitudinal movement thereon.

6. In a trimming machine of the class described a shaft, a rotary cutting trimmer on the shaft, an abutment on the shaft, a slotted member movably associated in blade intermeshing relation with the rotary cutter, a sleeve connected with the slotted member adapted to engage against the said abutment to limit the movement of the slotted member forwardly towards the rotary cutter, spring means normally urging the said sleeve against said abutment and the slotted member forwardly towards the rotary cutter, said spring means permitting movement of the slotted member away from the cutter and longitudinally of said shaft, and guide means receiving the slotted member therein including an annular portion overlying the rotary cutter in peripherally spaced relation therewith and providing a shoe abutting surface adapted to act as a guard to prevent excess cutting of a shoe during a trimming operation, and spring means normally urging said sleeve into such relation towards the cutter and permitting movement of the guard means longitudinally of the shaft away from the cutter, and means to hold the slotted member stationary with respect to the rotary cutter against any longitudinal movement with the axis of the rotary cutter.

7. In a trimming machine for shoes the combination of a rotary shaft, a rotary cutter for the shaft, a slotted member, spring means for urging the slotted member into blade intermeshing relation with the cutter, means to selectively hold the slotted member in a fixed relation with respect to the rotary cutter to prevent longitudinal movement along the shaft, a sleeve like guard member including a portion annularly surrounding the slotted member and the rear end of the rotary cutter and providing a rest surface in a plane at right angles to the axis of the shaft and lying peripherally outwardly of the cutter, and spring means urging said sleeve into abutment with the rotary cutter to a guarding relation with respect to the rotary cutter.

8. In a trimming machine of the class described a shaft, a rotary cutter for the shaft, an abutment on the shaft, means permitting adjustment of the abutment along the shaft, said shaft providing a forward annular edge, a guard sleeve telescopically disposed over the forward end of said abutment and providing an internal shoulder facing the

forward edge of the abutment, a spiral spring between said shoulder and the forward edge of the abutment normally urging the guard sleeve forwardly towards the rotary cutter, means to limit the forward movement of the guard sleeve towards the rotary cutter, said rotary cutter including a forward surface peripherally lying out-

wardly of the rotary cutter to provide a shoe rest to guide the shoe during a cutting operation, and means to connect the guide sleeve with the abutment to prevent longitudinal movement of the guide sleeve along the axis of the shaft. 10

JAMES H. GEORGELIS.
